LAMP MANUFACTURING APPARATUS

Adolph E. Drobish, Oak Park, Ill., assignor to
 Western Electric Company, Incorporated, New
 York, N. Y., a corporation of New York

Application June 12, 1940, Serial No. 340,028

8 Claims. (Cl. 176—3)

This invention relates to lamp manufacturing apparatus and more particularly to improvements in lamp exhausting and tipping-off machines of the type disclosed in Van Sant Patent No. 2,023,628.

Machines of the type referred to usually comprise a rotary turret having a series of exhaust heads, each adapted to receive an electric lamp assembly having an externally projecting exhaust tube through which the lamp is evacuated. The turret is intermittently rotated to advance each exhaust head through a series of evacuating stations and then to a tipping-off station where the evacuated lamps are tipped-off and deposited into a suitable collecting receptacle. The scrap exhaust tubes are then extracted from the exhaust heads and are deposited into a suitable scrap glass receptacle. Mechanism is usually provided for preventing the tipping-off of defective lamp assemblies. In some instances, however, the machine fails to tip-off satisfactory lamp assemblies because of some defect in or faulty operation of some part of the machine. All untipped-off lamp assemblies are usually extracted from the exhaust heads by means of the scrap exhaust tube extractor and are in effect, rejected by the machine by being deposited in the same scrap glass receptacle in which the scrap exhaust tubes are collected, thus rendering it difficult to detect machine defects and to salvage the improperly rejected lamp assemblies.

Objects of the present invention are to provide, in machines of the type referred to, means whereby improperly rejected lamp parts may be salvaged economically, and means whereby machine defects, such as result in the production of defective parts or in the improper rejection of satisfactory parts, may be detected quickly and with minimum effort.

In accordance with one embodiment of the invention, there is provided, in conjunction with a lamp exhausting and tipping-off machine, mechanism for separating untipped-off lamp assemblies from the scrap exhaust tubes in order to facilitate salvaging those which are satisfactory. Mechanism is also provided for automatically sorting the untipped-off lamp assemblies in accordance with the particular exhaust heads from which they are extracted so that machine defects can be detected expeditiously and with minimum effort.

A preferred embodiment of the invention is illustrated in the accompanying drawings, in which

Fig. 1 is a fragmentary plan view of a lamp exhausting and tipping-off machine equipped with

a separating and sorting mechanism embodying the invention;

Fig. 2 is an enlarged plan view, partly in section, of the separating and sorting mechanism;

Fig. 3 is a vertical sectional view taken on line 3—3 of Fig. 2;

Fig. 4 is a fragmentary side elevational view of the separating mechanism, looking from the left of Fig. 3;

Fig. 5 is a fragmentary sectional view taken on line 5—5 of Fig. 4;

Fig. 6 is a detail sectional view taken on line 6—6 of Fig. 3;

Fig. 7 is a longitudinal sectional view of an untipped-off lamp assembly, and

Fig. 8 is a similar view of a tipped-off lamp and the scrap exhaust tube.

Referring to the drawings, there is illustrated in Fig. 1 a portion of an electric lamp exhausting and tipping-off machine of the type disclosed in the above-referred-to Van Sant patent. This machine is capable of exhausting and tipping-off electric lamp assemblies 25 (Fig. 7), which comprise a tubular bulb 26 having sealed therein a filament supporting stem 27 having an externally projecting tubular portion 28 through which the lamp is evacuated. After being evacuated, the lamp is tipped-off or separated from the exhaust tube 28, as shown in Fig. 8. The machine comprises a circular series of exhaust heads 30, 30 arranged adjacent the periphery of a rotary circular carrier or turret 31, only a portion of which is shown in the drawings. Suitable mechanism (none shown) is provided for imparting an intermittent rotary motion to the turret 31, whereby the series of exhaust heads are advanced, step by step, through a series of stations. Each exhaust head, upon arriving at the loading station, designated in Figs. 1 and 2 by the reference numeral 1, is adapted to receive a lamp assembly 25, which is inserted, exhaust tube downward, into the exhaust head and is thereby connected to the usual evacuating system of the machine. After passing through a series of evacuating stations, each lamp arrives at a tipping-off station, which is designated in Fig. 1 by the reference numeral 23. At this station, satisfactory lamps are tipped-off by means of a torch 35. The tipped-off lamps are deposited into a tube 36 leading into a suitable collecting receptacle 37. At station No. 24, which immediately follows the tipping-off station, an extractor device 40 extracts scrap exhaust tubes and untipped-off lamp assemblies from the exhaust heads so that each head is conditioned to receive

another lamp assembly upon arriving at the loading station.

In accordance with the present invention, mechanism is provided for automatically separating the untipped-off lamp assemblies from the scrap exhaust tubes and for automatically sorting them in accordance with the particular exhaust heads from which they are extracted. This mechanism comprises a separating device 44 and a series of pans or receptacles 45, 45, one for each exhaust head 30. Each of these receptacles is removably supported upon a shelf-like supporting bracket 47 fixed to the turret 31. The receptacles are preferably positioned adjacent their associated exhaust heads and bear suitable identification markings (none shown) to facilitate identifying them with their associated exhaust heads when removed from the machine.

The separating device 44 comprises a vertical tube 48 mounted adjacent a scrap exhaust tube receiver 50 on a bracket 49 fixed to a stationary base portion 46 of the machine frame. The tube 48 extends upwardly beyond the upper end of the scrap exhaust tube receiver and has an elongated entrance slot 51 (Fig. 4) extending longitudinally thereof on the side adjacent the scrap exhaust tube receiver. A pair of spaced vertical guide plates 53, 53 project laterally from opposite sides of slot 51 and have depending portions 54, 54 (Figs. 3 and 4) extending into the upper end of the scrap exhaust tube receiver. Projecting upwardly from the guide plates 53 are a pair of supporting pins 55, 55 having a pair of spaced separating fingers 56, 56 attached to their upper ends. These separating fingers are in vertical alignment with the guide plates and slope downwardly toward the tube 48, terminating just inside the entrance slot 51 thereof.

The separating fingers 56 and guide plates 53 are spaced apart a sufficient distance to permit the free passage therebetween of the exhaust tube 28 of the lamp assembly, but not the larger diameter bulb portion 26 thereof. Thus, scrap exhaust tubes pass freely between the separating fingers and guide plates and drop into the upper end of scrap exhaust tube receiver 50, but untipped-off lamp assemblies are directed by the separating fingers into the tube 48. An external boss or projection 58 is provided on tube 48 just above its entrance slot 51, whereby untipped-off lamp assemblies are tilted as they slide down the separating fingers, as shown in Fig. 5, and are thereby positively directed into the tube. The lower end of this tube is curved, terminating in a substantially horizontal trough-like portion 59, which is positioned so as to guide each lamp assembly into the particular receptacle 45 which is associated with the exhaust head 30 from which the lamp assembly was extracted.

In the operation of the machine, each of the series of exhaust heads is indexed through the several stations and finally arrives at extracting station 24. Each exhaust head dwells at this station while the extractor 40 swings into the position in which it is shown in Figs. 1 and 2, extracts the scrap exhaust tube or untipped-off lamp assembly from the exhaust head and carries it to a position directly above scrap exhaust tube receiver 50 and between separating fingers 56 and guide plates 53, as illustrated in broken lines in Figs. 3 and 4. The jaws of the extractor then open, thus releasing the scrap exhaust tube or lamp assembly. If it is a scrap exhaust tube,

it passes freely between the separating fingers and guide plates and drops into the scrap tube receiver 50, which directs it into a suitable scrap glass receptacle (none shown). If it is an un-

5 tipped-off lamp assembly, it slides down the separating fingers into the tube 48, which directs each lamp assembly into that receptacle 45 which is associated with the particular exhaust head from which the lamp assembly was extracted.

10 The turret is then indexed to advance the next exhaust head to the extracting station and the above operations are repeated. Thus, all un-tipped-off lamp assemblies are automatically separated from scrap exhaust tubes and each un-tipped-off lamp assembly is automatically associated with the particular exhaust head from which it was extracted, whereby machine defects may be detected quickly and with minimum effort.

15 20 It should be understood that the invention is not limited to the particular embodiments thereof herein illustrated and described, except insofar as is defined by the appended claims.

What is claimed is:

25 1. In a lamp exhausting and tipping-off machine comprising a rotary carrier having a series of exhaust heads for carrying electric lamp and exhaust tube assemblies through a series of stations, a series of receptacles, one for each exhaust

30 head, means adjacent one of said stations for extracting scrap exhaust tubes and untipped-off lamp assemblies from said exhaust heads, a separating mechanism for receiving the extracted parts from said extracting means and for separating the untipped-off lamp assemblies from the scrap exhaust tubes, and means for directing the untipped-off lamp assemblies into the receptacles associated with the respective exhaust heads from which said assemblies are extracted.

35 40 2. In a lamp exhausting and tipping-off machine having a series of heads movable through a series of stations, each head capable of supporting an electric lamp and exhaust tube assembly during evacuating and tipping-off operations, an extractor mechanism at one of said

45 45 stations for extracting untipped-off lamp assemblies and scrap exhaust tubes from said heads upon their arrival at said station, and a separating mechanism for receiving the extracted parts from said extractor mechanism and for separating the untipped-off lamp assemblies from the scrap exhaust tubes.

50 55 3. In a lamp exhausting and tipping-off machine having a series of heads movable through a series of stations, each head capable of supporting an electric lamp and exhaust tube assembly during evacuating and tipping-off operations, an extractor mechanism at one of said stations for extracting untipped-off lamp assemblies and scrap exhaust tubes from said heads upon their arrival at said station, a separating mechanism disposed adjacent said station for receiving the extracted parts directly from said extractor mechanism and for separating the untipped-off

60 65 70 lamp assemblies from the scrap exhaust tubes, and mechanism for automatically sorting the extracted untipped-off lamp assemblies in accordance with the respective heads from which they are extracted.

75 80 4. In a lamp exhausting and tipping-off machine having a series of heads which are progressively advanced through a series of stations, each head capable of supporting an electric lamp and exhaust tube assembly during evacuating and

tipping-off operations, an extractor mechanism at one of said stations for extracting untipped-off lamp assemblies from said heads upon their arrival at said station, and mechanism for automatically sorting the extracted untipped-off lamp assemblies in accordance with the respective heads from which they are extracted.

5. In a lamp exhausting and tipping-off machine having a series of heads which are progressively advanced through a series of stations, each head capable of supporting an electric lamp and exhaust tube assembly during evacuating and tipping-off operations, an extractor mechanism at one of said stations for extracting untipped-off lamp assemblies from said heads upon their arrival at said station, a series of receptacles, one associated with and disposed adjacent each head, and guiding means for directing the extracted untipped-off lamp assemblies from said extractor mechanism into the receptacles associated with the respective heads from which said lamp assemblies are extracted.

6. In a lamp exhausting and tipping-off machine having a series of heads movable through a series of stations, each head capable of supporting an electric lamp and exhaust tube assembly during evacuating and tipping-off operations, an extractor mechanism at one of said stations for extracting untipped-off lamp assemblies and scrap exhaust tubes from said heads upon their arrival at said station, a separating mechanism for receiving the extracted parts from said extractor mechanism and for separating the untipped-off lamp assemblies from the scrap exhaust tubes, a series of receptacles, one associated with and disposed adjacent each head, and means for directing the untipped-off lamp assemblies from said separating mechanism into the re-

ceptacles associated with the respective heads from which said lamp assemblies are extracted.

7. In a lamp exhausting and tipping-off machine having a series of heads movable through a series of stations, each head capable of supporting an electric lamp and exhaust tube assembly during evacuating and tipping-off operations, an extractor mechanism at one of said stations for extracting untipped-off lamp assemblies and scrap exhaust tubes from said heads upon their arrival at said station, and a separating mechanism for separating the untipped-off lamp assemblies from the scrap exhaust tubes, said separating mechanism comprising a member for receiving untipped-off assemblies, and guiding means for directing said lamp assemblies into said receiving member.

8. In a lamp exhausting and tipping off machine having a series of heads movable through a series of stations, each head capable of supporting an electric lamp and exhaust tube assembly during evacuating and tipping-off operations, an extractor mechanism at one of said stations for extracting untipped-off lamp assemblies and scrap exhaust tubes from said heads upon their arrival at said station, a scrap receiver for receiving the scrap exhaust tubes, a separate receptacle adjacent each head for receiving the untipped-off lamp assemblies, a guide tube for directing the untipped-off lamp assemblies into the receptacles adjacent the respective heads from which they are extracted, and spaced guide fingers for directing the untipped-off lamp assemblies into said guide tube, said guide fingers being spaced apart and arranged to permit the scrap exhaust tubes to pass therebetween and drop into said scrap receiver.

ADOLPH E. DROBISH.
